APPARATUS FOR LOOSENING YARN
PACKAGES

Frederick Farwell Long, Chester, Pa., assignor to
American Viscose Corporation, Wilmington,
Del., a corporation of Delaware

Application February 21, 1941, Serial No. 380,010

2 Claims. (Cl. 18—8)

This invention relates to improvements in means for flexing and loosening yarn and thread packages. More particularly, the invention relates to improvements in means for flexing and loosening yarn and thread packages, such as rayon cakes, to make them more permeable to treating liquids.

In the manufacture of rayon by the box spinning method, the yarn is collected in an annular form or cake which is later subjected to various liquid treatments. Treating liquids will not readily penetrate a large cake and where such a cake is to be treated it is desirable to first loosen or flex the cake to make it more permeable. Manual methods and apparatus for doing this have been suggested before but it has been found that these operations consume an excessive amount of time and often cause tangling and damage to the yarn.

The principle object of this invention is to provide improved means for flexing and loosening yarn and thread packages to make them more permeable.

A further object of this invention is to provide an improved means for flexing and loosening rayon cakes which is rapid in its operation and does not tangle or damage the yarn.

Other objects and advantages of the invention will be apparent from the specification and the accompanying drawing.

In the drawing is shown a perspective view of a preferred embodiment of the invention.

The invention as shown in the drawing comprises a table or plate member 1 on which the pulleys 2 and 3 on vertical shafts are mounted. A continuous belt-like member 4 having projecting rib-like members 5 passes around the pulleys. The pulleys are driven by suitable means to move the belt-like member in the direction shown by the arrow. A vertical presser plate member 6, having vertical rib-like members 15, is mounted on the table opposite and spaced from a portion of the belt passing between the pulleys. The presser plate is supported at one end on the bracket 7 which is fastened to the table by the bolt 8 which passes through a slot 9 in the bracket so that the position of this end of the presser plate may be adjusted transversely relative to the belt. The other end of the presser plate is supported by the rod 11 which passes through the bracket 10 fastened to the table. The presser plate is urged toward the belt by the spring 13 positioned on the rod between the presser plate and the bracket. This end of the presser plate may be adjusted relative to the belt by the nut 12 which is thread-

ed on the end of the rod. A conveyor belt member 14 is positioned to travel between the belt-like member 4 and the presser plate substantially flush with the top of the table. Suitable means are provided for moving the conveyor belt in the direction shown by the arrow.

In the operation of the device yarn packages or cakes 16, either with or without a protective covering member, are placed upright on the conveyor belt and are passed between the presser plate and the belt-like member 4. The distance between the presser plate and the belt is less than the diameter of the cakes or packages. The cakes or packages are rotated about their axes and are crushed while passing between the belt and the presser plate which causes them to be flexed and loosened. The ribs on the belt-like member and the presser plate insure the movement of the cakes or packages through the device and also aids in flexing and loosening them. The presser plate may be adjusted relative to the belt 4 to accommodate cakes or packages of various sizes and to also vary the degree to which they are loosened or flexed. With this device, yarn cakes or packages may be rapidly flexed or loosened without tangling or damaging the yarn.

While a preferred embodiment of the invention has been shown, it is to be understood that changes and variations may be made without departing from the spirit and scope of the invention as defined by the appended claims.

What I claim is:

1. An apparatus for loosening a yarn package comprising opposed presser members, one of said presser members comprising a plate-like member, the other comprising a belt-like member, said belt-like member being adapted to rotate the yarn package and move the yarn package between the plate-like member and the belt-like member, and additional means positioned between the presser members for supporting and moving the yarn package between the presser members.

2. An apparatus for loosening yarn packages comprising opposed upright presser members, one of said presser members comprising a belt-like member supported on vertically mounted pulleys, the other comprising a plate-like member, said belt-like member being adapted to continuously rotate yarn packages and move yarn packages between the belt-like member and the plate-like member, and a conveying means positioned between the presser members to assist in moving yarn packages between the presser members.

FREDERICK FARWELL LONG.
